UNITED STATES PATENT OFFICE.

MYRON COSSEY, OF BROOKLYN, NEW YORK, ASSIGNOR TO RELIANCE
BALL BEARING DOOR HANGER COMPANY, OF NEW YORK, N. Y., A
CORPORATION OF NEW YORK.

DOOR-HANGER.

No. 809,781.

Specification of Letters Patent.

Patented Jan. 9, 1906.

Application filed August 26, 1903. Serial No. 170,777.

To all whom it may concern:

Be it known that I, MYRON COSSEY, a citizen of the United States, residing in the borough of Brooklyn, in the county of Kings, city and State of New York, have invented certain new and useful Improvements in Door-Hangers, of which the following is a specification.

My invention relates to means for hanging laterally-moving doors.

10 I will describe a structure embodying my invention and then point out the novel features in claims.

In the accompanying drawings, Figure 1 is a view, partly in side elevation and partly 15 in vertical cross-section, of a construction showing a laterally-movable door and embodying my invention. Fig. 2 is a cross-section view of the construction shown in Fig. 1 and taken on the line *x x* of Fig. 1. Fig. 3 is a 20 detail perspective view of one form of carrier for antifriction devices, and Fig. 4 a similar view of a slightly-modified form. Fig. 5 is a view in side elevation, illustrating modifications of my invention; and Fig. 6 is a detail 25 cross-section view taken on the line *y y* of Fig. 5.

In the drawings similar letters and figures of reference designate corresponding parts.

I will premise that in this class of devices 30 where the part from which the door is suspended travels on antifriction devices it is important that the antifriction devices while left perfectly free to roll or travel along their tracks or supports should be kept in proper 35 relative positions, or should the antifriction devices be arranged in sets the sets should be kept in proper relative positions. Where this is accomplished, a much better support is obtained for the door at all points of its 40 travel. It is also important that the antifriction devices or sets of devices should be in position to support the door at the end of each full lateral movement of the door.

Referring to the drawings, 1 designates a 45 suitable base-plate, and 2 3 4 bars or rails extending longitudinally of the base-plate 1. They may be of any proportions in cross-section and of any lengths. The bars 2 and 3 constitute one element and bar 4 another element, and one of these elements is adapted to have movement with respect to the other—that is to say, the bars 2 3 may be fixed against movement and the bar 4 may have movement

between and along the bars 2 3, or the bar 4 may be fixed against movement and the bars 55 2 and 3 have movement along the bar 4. In either case the door is suspended from the movable bar or bars. In any case the movable bar or bars may be termed a "carriage" and the fixed bar or bars a "track." In the 60 preferred form of my invention the bars 2 and 3 are fixed to the base-plate 1 and constitute the tracks, while the bar 4 is movable between and along the bars 2 3 and constitutes the carriage. I shall for convenience 65 hereinafter refer to the bars 2 3 as the tracks and the bar 4 as the carriage.

D designates a door, which is suspended by suitable hangers H from the carriage 4.

The carriage 4 and the tracks 2 and 3 are 70 provided along their adjacent edges with grooves substantially circular in cross-section for receiving antifriction devices, which, as here shown, are in the form of balls.

The antifriction devices between the carriage 4 and the tracks constitute what may be termed a "set," or in the case of at least four antifriction devices arranged in pairs and one antifriction device in each pair being arranged above the other antifriction device 75 of the same pair each pair of antifriction devices may constitute a set. In order that the antifriction devices may be kept in their relative positions, I provide suitable carriers. These carriers comprise strips having openings 80 for the antifriction devices and means by which the carriers are all connected together in order that all the antifriction devices may be relatively spaced apart. There may be any number of carriers, which may be 85 connected in any desired manner. In any case there should be at least four antifriction devices, as I have found by experience that at least this number is necessary to accomplish the results desired, which I have already set forth immediately following my description of the drawings. In the construction 90 where only four balls are used they will be arranged two in each set.

Referring now to Figs. 1, 2, and 3, the carriers 100 preferably comprise two vertically-arranged strips or pieces 5, each provided with two openings 5^a, and a longitudinally-extending strip 6, which is suitably joined to the two strips 5, or the strip 6 may be integral 105 with the two strips 5. The strip 6 serves to

connect the carriers and to relatively space them, and therefore the antifriction devices. An antifriction device 9 is placed in each opening 5^a. The carriers 5 in this form are 5 ranged one above the other. Referring now to Fig. 4, the carriers are so arranged as not to have the antifriction devices opposite to each other, as in Fig. 3. Referring now to Figs. 5 and 6, the carriers for the sets of antifriction devices are independent of each other, and each carrier consists of a strip 6^a, provided with suitable openings. It will be 10 seen that upon a movement of the door D laterally in either direction the antifriction devices on both sides of the carriage will move to support the carriage in any position to which it may be moved between the two tracks, and by reason of the spacing of the antifriction devices relatively to each other 15 and maintaining this spacing at all times a uniform support for the carriage is always provided.

Should the antifriction devices be prevented from moving with the carriage—as, 20 for example, by their sticking in the grooves in the tracks—so that the carriage will have a movement relatively to the held antifriction devices, I provide means for causing the antifriction devices to be moved by the carriage 4 upon a full lateral movement of the door in either direction. As shown, this may be accomplished by providing pins or studs 8 at the ends of the carriage 4, which engage 25 with the carrier to cause it to move with the carriage. In the forms of carriers in which the cages are joined only one pin or stud 8 is necessary at each end of the carriage. These pins or studs 8 act in connection with the stops 10 to always have the antifriction devices in the position which will afford the 30 best support for the door. In practice the proper position for the antifriction devices is dependent mainly upon the door and is determined in part by the position of the carriage to the tracks when the door is in an extreme position. After this proper position 35 has been determined in each case the pins 8 and stops 10 may be so arranged that the antifriction devices will be moved by them 40 in case the antifriction devices should not always move with the carriage to their proper 45 position.

In the accompanying drawings I have 50 shown the door hanging by hangers from the intermediate bar or track and the intermediate bar or track being movable between the outside bars, which are fixed. It will depend, however, upon the precise structural details of the building or other structure as 55 to how the various parts comprising my invention shall be attached to the door. For example, the intermediate bar might be fixed and immovable and secured to a fixed portion of the structure. In this case the outside bars, which might be formed of either

one or two pieces, would be secured to the door.

What I claim as new, and desire to secure by Letters Patent, is—

1. In a door-hanger the combination with 70 two outside bars and an intermediate bar, one of said elements being movable with respect to the other, of a plurality of movable antifriction devices on each side of the intermediate bar and between it and the outside 75 bars, and means for retaining a plurality of antifriction devices on one side of the intermediate bar in position relatively to a plurality of antifriction devices on the other side thereof. 80

2. In a door-hanger the combination, with two outside bars and an intermediate bar, one of said elements being movable with respect to the other, of a plurality of movable antifriction devices on each side of the intermediate bar and between it and the outside 85 bars, and means for retaining a plurality of antifriction devices on one side of the intermediate bar in position relatively to a plurality of antifriction devices on the other side 90 thereof, said antifriction devices being divided equally to provide an equal number thereof on both sides of the intermediate bar.

3. In a door-hanger the combination, with two bars, of a part movable between and along the bars, a plurality of antifriction devices between each bar and the said part, and means for spacing and for maintaining the spacing of antifriction devices on each side 95 of said part. 100

4. In a door-hanger the combination, with two outside bars and an intermediate bar, one of said elements being movable with respect to the other, of a spacing-strip provided on each side with a plurality of projections 105 each having an aperture therein, and movable antifriction devices arranged in said apertures.

5. In a door-hanger the combination, with two outside bars and an intermediate bar, 110 one of said elements being movable with respect to the other, of a plurality of movable antifriction devices arranged on each side of the intermediate bar and between it and the adjacent outside bar, a retainer for each antifriction device and a strip securing together 115 each and all of said retaining devices on both sides of the intermediate bar.

6. In a door-hanger the combination, with a movable body, of a plurality of movable 120 antifriction devices arranged on each side thereof, and means for retaining a plurality of antifriction devices on one side of said movable body in fixed relative position with regard to a plurality of antifriction devices 125 on the other side thereof.

7. In a door-hanger the combination, with two outside bars and an intermediate bar, one of said elements being movable with respect to the other, of a plurality of movable 130

antifriction devices arranged on each side of said intermediate bar and between it and the adjacent outside bar, and a movable spacing device comprising a strip provided with a plurality of projections from each side thereof—each of said projections having its outer end bent at substantially right angles to the strip and provided with an aperture and arranged between the intermediate bar and the adjacent outside bar and containing in said aperture one of the aforesaid antifriction devices.

8. In a door-hanger the combination, with two outside bars and an intermediate bar, one of said elements being movable with respect to the other, of a plurality of movable antifriction devices on each side of the intermediate bar and between it and the outside bars, and means for retaining all of said antifriction devices in fixed relative position.

9. In a door-hanger the combination, with two outside bars and an intermediate bar, one of said elements being movable with respect to the other, of a plurality of movable antifriction devices on each side of the intermediate bar and between it and the outside

bars, and a member having its major portion adjacent to said intermediate bar and portions thereof bent to project between the intermediate bar and each of said outside bars, 30 said bent portions being provided with apertures in which said antifriction devices are contained.

10. In a door-hanger the combination with two outside bars and an intermediate bar, 35 one of said elements being movable with respect to the other, of a plurality of movable antifriction devices arranged on each side of said intermediate bar, a spacer for retaining a plurality thereof on one side in position relatively to a plurality on the other side; and pins arranged near the ends of said bars to engage said spacer and readjust it relatively to the bars when it becomes displaced.

In testimony whereof I have signed my 45 name to this specification in the presence of two subscribing witnesses.

MYRON COSSEY.
